UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DUMP-CAR.

1,069,763.

Specification of Letters Patent. Patented Aug. 12, 1913.

Application filed March 20, 1913. Serial No. 755,590.

To all whom it may concern:

Be it known that I, ARGYLE CAMPBELL, a citizen of the United States, residing in Chicago, in the county of Cook and State of Illinois, have invented a new and useful Improvement in Dump-Cars, of which the following is a specification.

This invention relates to improvements in dump cars, and more particularly to the center sill construction of such cars.

An object of the invention is to provide a dump car, the center sill construction of the underframe of which is cheap to manufacture, strong, well adapted to withstand buffing strains, and which is so constructed that practically no part of the load will remain in the car above the center sill when the load is dumped.

Another object of the invention is to provide a dump car having a box-like center sill disposed below the normal floor level of the car, the upper portion of the sill being formed by a rolled plate member of a substantially inverted V shape, having a narrow, flat upper portion to which is attached a longitudinally extending floor plate.

The invention furthermore consists in the improvements in the parts and devices and in the novel combinations of parts and devices herein shown, described or claimed.

In the drawing forming a part of this specification, Figure 1 is a cross sectional view of an interchangeable general service and hopper car embodying my improvements. Fig. 2 is an enlarged, detail sectional view of the center sill construction shown in Fig. 1, and Fig. 3 is a sectional view of another form of center sill embodying my invention.

In the drawing, the interchangeable general service and hopper car is shown as having an end 10, sides 11, hoppers 12, center sill A (more particularly hereinafter described), hinged side dump floor doors 13, the same being hinged closely together near the longitudinal center of the car approximately at the floor level, and door operating mechanism including longitudinally extending shafts 14 and chains 15. Each floor door 13 is detachably hinged at its inner end as at 16, shown in the right hand part of Fig. 1, said doors being adapted to be dropped to a position to form the bottom of a hopper, as shown at 13^a on the left hand

portion of Fig. 1, the lower ends of the door being supported on suitable hinge butts 17, the latter in turn being fixed to brackets 18 secured to the end hopper sheets 19. Each hopper 12 is also provided with a lower, hinged, center dump hopper door 20, operated by mechanism including a longitudinally extending shaft 21 and chains 22, said doors 20 being pivoted to the under side of the center sill construction. The interchangeable features of the hopper car above described form no part of this invention, the same being shown, described and claimed in the patent issued to me, No. 1,054,087, dated Feb. 25, 1913.

The center sill construction A, shown in Fig. 1, comprises two lower, longitudinally extending members 23, the same being in the form of channels having their flanges turned inwardly, and secured to the tops of the channels is a longitudinally extending plate 24, the latter being of substantially inverted V shape, and having an upper, relatively narrow, flat, horizontal portion 25, to which is secured a somewhat wider, longitudinally extending floor plate 26. The lower edges 27 of the plate 24 are secured to the outer faces of the channels 23 by rivets or other suitable means, as shown in Fig. 2.

With the construction above described, it will be seen that the floor dump doors of the car may be hinged quite closely together, as shown in Fig. 1, the hinge connections being located between the sloping sides of the plate 24 and the horizontal floor plate 26, and being protected by the latter. By making the plate 24 in the form as shown and described, I am enabled to do away with any T's, I's or angles above the channels, such as have hitherto been used in order to narrow the upper portion of the center sill construction to bring the hinge points of the floor doors together, and by forming the plate 24 with the narrow, flat portion 25, I provide a substantial support to which the floor plate 26 may readily be attached.

In Fig. 3, the center sill construction is shown as formed of a pair of outwardly turned channels 23^a and an upper, substantially inverted V-shaped plate 24^a, the latter having a relatively narrow, horizontal, flat portion 25^a, and having its lower edge portions 27^a outwardly extended and secured to the top flanges of the channels 23^a, the longitudinally extending floor plate 26^a be-

ing secured to the upper portion of the center sill construction similar to the arrangement shown in Figs. 1 and 2.

I claim:—

- 5 1. In a car of the character described, in combination: a car body having floor door openings; side-dump floor doors hinged at their inner, longitudinal edges for said door openings; and an underframe including a center sill having longitudinally extending, spaced, vertical lower portions and an inverted, V-shaped, upper portion, all substantially below the floor level, said V-shaped upper portion having also a flat integral top 10 to which a floor plate may be secured, whereby the doors may be hinged closely together near the longitudinal center of the car approximately at the floor level, substantially as specified.
- 15 2. In a car of the character described, in combination: a car body having floor door openings; side-dump floor doors hinged at their inner, longitudinal edges; and an underframe including a center sill comprising 20 lower, longitudinally extending, spaced channels and an inverted, V-shaped upper

rolled plate, said channels and plate being disposed substantially below the floor level, whereby the floor doors may be hinged closely together near the longitudinal center 30 of the car and approximately at the floor level, substantially as specified.

3. A car of the character described, including, in combination: a car body provided with a side dump floor door hinged 35 at its inner, longitudinal edge; and an underframe, including a center sill, comprising a pair of longitudinally extending, spaced channels having a substantially inverted V-shaped plate secured to the tops 40 thereof, said plate having a relatively narrow, flat, horizontal top portion to which is secured a longitudinally extending floor plate, substantially as specified

In testimony whereof, I have hereunto 45 signed my name in the presence of two subscribing witnesses.

ARGYLE CAMPBELL.
